(57) **CLAIM**

The ornamental design for a tile sensor unit, as shown and described.

DESCRIPTION

FIG. 1 is a front perspective view of a tile sensor unit according to our new design;

FIG. 2 is a front view of a tile sensor unit thereof;

FIG. 3 is a rear view of a tile sensor unit thereof;

FIG. 4 is a right side view of a tile sensor unit thereof;

FIG. 5 is a left side view of a tile sensor unit thereof;

FIG. 6 is a top view of a tile sensor unit thereof; and,

FIG. 7 is a bottom view of a tile sensor unit thereof.
